UNITED STATES PATENT OFFICE.

CHARLES J. NELSON, OF MAYWOOD, ILLINOIS, ASSIGNOR TO AMERICAN CAN COMPANY,
OF NEW YORK, N. Y., A CORPORATION OF NEW JERSEY.

MECHANISM FOR OPERATING ON CAN-BODIES.

1,173,302.

Specification of Letters Patent. Patented Feb. 29, 1916.

Application filed May 12, 1913. Serial No. 767,098.

To all whom it may concern:

Be it known that I, CHARLES J. NELSON, a citizen of the United States, residing in Maywood, in the county of Cook and State 5 of Illinois, have invented a new and useful Improvement in Mechanism for Operating on Can-Bodies, of which the following is a specification.

This invention relates to mechanism for 10 operating on can bodies, and more particularly to that type of machine adapted for operating on irregularly shaped or noncircular can bodies.

One object of the invention is to provide 15 mechanism which will be adapted to necking-in, flange and curl rectangular or other non-circular can bodies, which may be made of tin or other material, and which is adapted to perform all of the above named operations 20 practically simultaneously or any one of said operations singly or any combination of them practically simultaneously.

Another object of the invention is to so 25 arrange the co-operative parts that the mechanisms may easily be adapted for beading irregularly shaped can bodies.

Another object of the invention is to so 30 arrange the mechanism that any of the parts may be easily replaced or repaired when the same become worn or broken in use.

The invention further consists in the improvements in parts and devices and in the novel combinations of parts and devices herein shown, described or claimed.

In the drawing forming a part of this 35 specification, Figure 1 is a sectional view showing a punch or horn or mandrel and die embodying improvements of the invention. Fig. 2 is an end view of the punch or horn 40 shown in Fig. 1. Fig. 3 is an end elevation of the die shown in Fig. 1. Fig. 4 is a sectional view, taken on the line 4—4 of Fig. 1, and looking in the direction of the arrows. Fig. 5 is an elevation, upon a somewhat reduced scale, showing one method of stripping the can bodies after the operations 45 have been performed thereon.

In the drawing, 10 denotes the horn or mandrel or punch, which, as shown, is rectangular in cross section, and forms part of the body forming horn of a can body forming machine, and which is provided with an end plate 11 rigidly secured thereto and spaced therefrom as by means of screws 12

and sleeves 13 in which the screws are in- 55 cased. The plate 11 is also additionally secured in place by means of dowel pins 14. Between the plate 11 and the extreme end of the horn or mandrel 10 are a plurality of 60 movable members 15, the same being normally held in contracted position by means of a coil spring 16, seated in a groove 17 formed in the sections 15. As more clearly 65 shown in Fig. 4, each of these movable or expensible sections 15 is provided with suitable recesses adapted to clear the sleeves 13 and dowel pins 14 in their movements in and out. The outer surface of the sections 15 is kept preferably in alinement with the outer 70 surface of the plate 11, and, as will be understood, the cross sectional area of the plate 11 and of the movable sections 15 when contracted is less than the cross sectional area of the main body 10 of the punch or mandrel in order to allow of the contracting or 75 necking-in of the mouth of the can body 18. The expandible die sections 15 are operated by means of a plunger 19, which is provided with a bevel or cam surface 20, and which is retained in place, as by means of a screw 21, 80 having its ends extending into a slot 22. The plunger 19 is normally pressed outward by means of a spring 23 seated in a socket in the horn or mandrel 10, and the plunger 19 is moved inwardly by means of a member 24 85 on the die 25. The die 25 comprises a main member 26, having a head 27 secured thereto by means of a bolt 127, said head being provided with a recess having a conical side 90 surface 28 and a flat bottom 29. Mounted in the head 27 and slidably therein are a plurality of die sections 30, said sections 30 being normally held expanded by means of a plurality of springs 31. Each of said die 95 sections 30 has an outer curved quadrant surface 32 adapted to engage with the conical surface 28 of the recess, and an inner right angle extension 33, by means of which the die sections are restrained in proper position between two plates 34 and 35, the latter being rigidly secured together as by means of rivets or bolts 36, passing through enlarged recesses or slots 37 in the movable die sections 30. The plates 34 and 35 and the die sections 30, which are movable in 100 unison therewith, are normally pressed outwardly by means of a plurality of springs 38 seated in sockets in the head 27. The

movable die sections 30 are limited in their outward movement relatively to the head 27 by means of a plate 39 removably secured to the head 27. Each of the movable die sections 30 is provided with a tapered mouth portion 40, a necking-in portion 41, 41' and a curling die portion or shoulder 42, it being understood that the portions 41 when the die and punch are moved together, coöperate 10 with the movable sections 15 of the horn or mandrel.

The horn or mandrel 10 is provided with a groove 43 extending therearound, in which is adapted to be seated a plurality of movable sectional thrust plates 44, the latter being provided with an open top flanging groove 45 located adjacent to the horn 10 and extending entirely therearound, it being apparent that part of the flanging groove is formed in each of the movable thrust plates 44. In Fig. 1 half of the plates 44 are shown removed. In Fig. 5 the die 25 is shown as provided with a pair of pivoted levers 46, the same having their outer ends normally pressed inwardly as by means of springs 47, said levers or arms 46 serving to strip the can body from the horn or mandrel 10 when the mandrel or horn and the die are separated.

In operation, the can bodies are placed on the horn or punch 10, either by having the same fed along the horn from the can body forming machine, while the thrust plates 44 are removed from the horn, or by placing the can bodies on the horn or mandrel from the right hand end of the latter, as viewed in Fig. 1. As the movable squeezing die and horn or mandrel are brought into engagement with each other, the plunger 24 operates the plunger 19, thereby expanding the movable punch sections 15 and simultaneously the movable die sections 30 are contracted as soon as the plate 35 engages with the end plate 11 of the punch, thereby contracting or necking in the can body between the movable sections 15 and 30, and also simultaneously forming a curl on the extreme outer edge of the can body and also causing a flange 50 to be formed on the inner end of the can body in the die flanging groove 45. The can is necked-in in this operation opposite the portions 41' of the movable sections of the die head, the portions 41 and the sections 15 serving to preserve the contour of the can body beneath the portion necked-in by the machine. As a result of the necking in operation, a straight but inset portion is formed by the sections 30 between the 60 curling shoulders 42 and the portions 41' necking-in the can. The finished can is formed as indicated in Fig. 1.

In case it is desired to form a bead on the can body, it will be apparent that it 65 would only be necessary to form beading

portions on the movable punch sections 15 and coöperating beaded grooves on the portions 41 of the movable die sections 30. In the drawings, the improvements have been shown as the same are used in connection with the horn or horn extension of a can body forming machine, that is, the punch or horn or mandrel is stationary and the squeezing or female die is made movable, but, as will be obvious, the squeezing die 75 may be made stationary and the punch or horn may be movable where the latter does not form an extension of the can body forming horn.

Many changes and variations may be 80 made in the various details of the mechanism without departing from the spirit of the invention, and all such changes and variations are contemplated as fall within the scope of the claims appended hereto. 85

What is claimed is:

1. In a machine of the class described, in combination, a horn or mandrel and die coöperating therewith and relatively movable to and from each other and adapted to 90 neck-in can bodies, said die comprising a head having a plurality of sections movably mounted thereon and adapted to be contracted, and springs acting at right angles to the sections and between the contiguous 95 sides of the sections for yieldingly holding them directly apart from each other.

2. In a machine of the class described, in combination, a horn or mandrel and a die coöperating therewith, said horn and die 100 being relatively movable to and from each other and adapted to neck-in can bodies, said horn having a plurality of movable expandable sections thereon, means for yieldingly holding the said sections in contracted 105 position, and a radially immovable end plate fixed on the said horn in advance of the said sections.

3. In a machine of the class described, in combination, a horn or mandrel provided with an internal necking-in die at the end thereof, and an external necking-in die coöperating therewith, said horn and die being movable relatively to and from each other, said external necking-in die comprising a head having a plurality of die sections movably mounted thereon and adapted to be contracted, and said horn being provided with a plurality of expandable members thereon and a radially immovable end plate in advance of the said expandable members. 110 115 120

4. In a machine of the class described, in combination, a horn or mandrel and a die coöperating therewith and relatively movable to and from each other and adapted to neck-in can bodies, said die comprising a head having a plurality of sections movably mounted thereon and adapted to be contracted, and springs 31 arranged and 125 130

acting between contiguous sections for normally retaining said movable sections in an expanded position.

5. In a machine of the class described, in combination, a horn or mandrel provided with an internal necking-in die at the end thereof, and an external necking-in die co-operating therewith, said horn and die being movable relatively to and from each other, said external necking-in die comprising a head having a plurality of die sections movably mounted thereon and adapted to be contracted, and said horn being provided with a plurality of expandible members thereon and a radially immovable end plate fixed on the said horn in advance of the said expandible members, means for normally maintaining said movable die sections in an expanded position, and means for normally maintaining said movable sections of the horn in a contracted position.

6. In a machine of the class described, in combination, a horn or mandrel provided with an internal necking-in die at one end thereof and an external necking-in die co-operating therewith, said external necking-in die comprising a plurality of sections adapted to be contracted, and a flanging die located at a point removed from the end of the horn and provided with a flange groove adjacent to and extending around the horn.

7. In a machine of the class described, in combination, a horn or mandrel having an internal necking-in die at one end thereof and a plurality of movable expandible sections mounted on the horn, and an external necking-in die co-operating therewith, said two dies being relatively movable to and from each other, and said external necking-in die comprising a head having a plurality of die sections movably mounted thereon and adapted to be contracted, and a flanging die located at a point removed from the end of the horn and provided with a flanging groove.

8. In a machine of the class described, in combination, a horn or mandrel and a die co-operating therewith and relatively movable to and from each other and adapted to neck in can bodies, said die comprising a head having a plurality of die sections and movably mounted thereon and adapted to be contracted, each of said die sections being provided with a curling portion.

9. In a machine of the class described, in combination, a horn or mandrel having an internal necking-in die at one end thereof and a plurality of movable, expandible sections mounted on the horn, and an external necking-in die co-operating therewith, said two dies being relatively movable to and from each other, and said external necking-in die comprising a head having a plurality of die sections movably mounted thereon

and adapted to be contracted, and a flanging die located at a point removed from the end of the horn and provided with a flanging groove.

10. In a machine of the class described, in combination, a horn or mandrel and an external necking-in die co-operating therewith, said parts being relatively movable to and from each other, said die comprising a head having a plurality of sections movably mounted thereon, pressed yieldingly apart and adapted to be contracted, each of said sections being provided with a curling shoulder.

11. In a machine of the class described, in combination, a horn or mandrel having an internal necking-in die at the end thereof and an external necking-in die co-operating therewith and relatively movable to and from each other, said external necking-in die comprising a head provided with a recess having a cam surface and a plurality of sections movably mounted in said recess and adapted to be contracted by said cam surface, and springs acting at right angles to the sections and between the contiguous sides of the sections for yieldingly holding them directly apart from each other.

12. In a machine of the class described, in combination, a horn or mandrel having an internal necking-in die at the end thereof and an external necking-in die co-operating therewith and relatively movable to and from each other, said external necking-in die comprising a head provided with a recess having a cam surface and a plurality of sections movably mounted in said recess and adapted to be contracted by said cam surface, and springs acting at right angles to the sections and between the contiguous sides of the sections for yieldingly holding them directly apart from each other.

13. In a machine of the class described, in combination, a horn or mandrel provided with an internal necking-in die at one end thereof and an external necking-in die co-operating therewith, said dies being relatively movable to and from each other, and said external necking-in die comprising a head provided with a conical recess therein and having mounted in said recess a plurality of contractible die sections, a pair of parallelly arranged spaced plates movably mounted within said recess, a plurality of contractible die sections, a pair of parallelly arranged spaced plates movably mounted within said recess at the inner end thereof, each of said die sections having a portion thereof disposed between said plates and movable therewith, a resilient means for normally maintaining said plates, and die sections at the outer end of the recess.

14. In a machine of the class described, in combination, a horn or mandrel provided with an internal necking-in die at one end

thereof and an external necking-in die comprising a head provided with a conical recess therein and having mounted in said recess a plurality of contractible die sections, a pair of parallel arranged spaced plates movably mounted within said recess and at the inner end thereof, each of said die sections having a portion thereof disposed between said plates and movable therewith, a resilient means for normally maintaining said plates, and die sections at the outer end of the recess, and a flanging die located at a point removed from the end of the horn and having a flanging groove therein.

15. In a machine of the class described, in combination, a horn or mandrel provided with an internal necking-in die at the end thereof, and an external necking-in die comprising a head having a plurality of die sections movably mounted thereon and adapted to be contracted, and said horn being provided with a plurality of expansible members thereon, and means for stripping the can bodies from the horn.

CHARLES J. NELSON.
